PRESS FOR PRINTING SPOTS OF WAX
CARBON COMPOUNDGeorge A. Rutkoskie, Athens, Ohio, assignor to
The McBee Company, Athens, Ohio, a corpora-
tion of Ohio

Application May 23, 1934, Serial No. 727,022

7 Claims. (Cl. 101—340)

My invention relates to that class of machines such as described in my Reissue Patent No. 18,931, and more specifically to the utilization of a press of the cylindrical roller inking type for printing.

My invention has for its object to provide a construction whereby a standard press of this type may be changed so as to be adapted for printing spots of wax carbon compound. As stated in my patent above referred to, I have discovered that it is essential to maintain the rollers and type bed with which the carbon compound comes in contact at a predetermined temperature and that unless such temperature is maintained the work turned out by the press will be extremely unsatisfactory, although in appearance it looks all right.

The principal object of my invention is to accomplish this result by having every roller carrying the compound in contact with a heated roller. I have found in practice that if this is done the heated roller will maintain the unheated one at the required temperature so that the press will turn out satisfactory work.

A further object of my invention is to provide means whereby one of the three traveling rollers can be heated continuously during its travel thereby maintaining the temperature of the rollers which contact it.

My means of accomplishing the foregoing objects may be more readily understood by having reference to the accompanying drawings which are hereunto annexed and are a part of this specification, in which—

Fig. 1 is an elevation of one side of a platen press provided with my improvement;

Fig. 2 is an elevation of the other side of the press;

Fig. 3 is an enlarged top or plan view of the press equipped with my improvements;

Fig. 4 is an enlarged fragmentary detail of the upper part of the press as shown in Fig. 2;

Fig. 5 is an enlarged fragmentary detail view of the top of the other side of the press showing the means of driving the form rollers;

Fig. 5A is a fragmentary detail view of the inking rollers, the distributing roller being omitted for the sake of clearness;

Fig. 6 is a more or less diagrammatic view of a cross section of the press as shown in Fig. 3, standard parts being omitted as they are well understood;

Fig. 7 is a wiring diagram;

Fig. 8 is a front view of the type bed showing the tracks for the traveling rollers;

Fig. 9 is a cross section taken on the line 9—9 in Fig. 8;

Fig. 10 is a fragmentary view of the type bed;

Fig. 11 is an enlarged detail view of the commutator for the traveling roller;

Fig. 12 is a view of the same from another direction; and

Fig. 13 is a view of the means for keeping the flexible conductors tight.

Similar reference numerals refer to similar parts throughout the entire description.

As shown in the drawings the press is a standard press of this type and I shall therefore omit a description of the same except where the standard parts are altered by being equipped with my improvement.

The press is provided with an ink fountain 1, this fountain is adapted to contain a quantity of wax carbon compound which is melted by means of heating elements mounted adjacent the fountain as shown in my patent previously referred to.

The fountain is equipped with the usual blade 2 for regulating the amount of compound to be carried by the ink roller 3, adjusting screws 4 of the usual type being provided for this regulation. Inside of the ink fountain roller 3, I mount an electrical heating element 5. This element is preferably mounted in a cylindrical sleeve 6. The element 5 is provided with two lead wires 7 and 8 which are connected to commutator 9. This commutator is engaged by brushes 10 and 11 connected to electrical conductors 12 and 13 which lead to a source of electric current supply (not shown).

This commutator 9 is secured to the shaft 13' of the ink fountain roller which is positively driven by the means of a chain 14 engaged by a sprocket 15 mounted upon the shaft 13. The chain 14 is driven by sprocket (not shown) 40 mounted upon the counter shaft 16 of the press which is driven in the usual manner by means of a chain 17 which engages a sprocket 18 mounted upon the counter shaft 16, the chain being driven by a sprocket 19 mounted upon the main shaft 20 of the press.

The ductor roller 21 is carried by an arm 22 by means of which it is oscillated in the usual manner between the ink fountain roller 3 and the cylindrical inking roller 23. This latter roller is mounted upon a shaft 24 which carries a sprocket 25 which is driven by means of a chain 26 which is driven by a sprocket (not shown) mounted upon the counter shaft 16.

The cylindrical inking roller 23 is provided

with an electrical heating element 27, the shaft of which carries a commutator 28 which is connected by brushes to lead wires 29 and 30 for the purpose of conveying current to the heating element 27.

5 Distributing rollers 31, 33, and 34 are mounted in the conventional manner so as to contact with the surface of the cylindrical inking roller 23. The one end of the shafts of rollers 31, 33, 10 and 34 is carried in supports 35, 36, and 37. The other ends, as clearly seen in Fig. 5, are provided with spur gears 38, 39, and 40 which are driven by a gear 41 which is carried by the shaft 24 of the cylindrical inking roller.

15 As stated in my patent hereinbefore referred to, I have discovered that there is an entire absence of tack in the wax compound when it is heated to the temperature requested for satisfactory work. As a consequence it is necessary for all 20 of the parts which carry the compound be positively driven. By driving the distributing rollers in the manner described it will be apparent that an even distribution of the melted wax compound can be maintained on the surface of the inking 25 roller 23.

The vertical type bed 44 is provided with a plurality of electrical heating elements 45 one of which is shown in Fig. 10. As shown these are four in number and a thermo couple 46 is 30 mounted intermediate two inner ones for the purpose of affording means for controlling the heat. A printing plate 47 may be secured to the type bed 44 in the usual or conventional manner. The platen 48 is operated in a standard way 35 for presses of this type. There are two rollers 49 and 50, the function of which is to ink the printing plate 47 which is secured to the type bed 44. A distributing roller 51 rides the two inking rollers 49 and 50.

40 The distributing roller 51, is carried by a shaft 52 which is mounted above the two traveling form rollers 49 and 50, the roller 51 being in contact with each of them. These rollers 49 and 50 are mounted upon shafts 53 and 54 respectively. At 45 each end of the shafts 53 and 54, of the rollers 49 and 50, are provided wheels 70 and 71 which are not in line with each other but each roller wheel is adapted to register with one of two depressions 72 and 73 formed in the track 74, 50 with the result that both rollers 49 and 50 will come in contact with the cylindrical inking roller 23 at the same time. The roller 51 is provided 55 with an electrical heating element 55 which is suitably connected by means of a commutator 56 to brushes 57, the latter being connected to lead wires 58 and 59 leading to a suitable source of electric current supply (not shown). The form rollers 49 and 50 contact the surface of the cylindrical inking roller 23 from which it receives 60 the melted wax compound for the plate 47. In their rotation the roller 51 serves as a traveling distributor roller distributing the compound on the form rollers 49 and 50, as this group of rollers travels from the point of contact with the cylindrical inking roller 23 to and across the plate 65 47 which is secured to the type bed 44.

70 It is apparent from the foregoing description that the conductors 58 and 59 connecting the brushes 57 to the source of electric current supply must be flexible so as to permit this travel.

75 It has also been found desirable in practice to provide means for taking up the slack of these conductors as the rollers move from their extreme downward position, shown in Figs. 1 and 2,

to their extreme upward position shown in Figs. 4 and 6.

I accomplish this result by means of a reel 60 which is carried on any suitable mounting intermediate the traveling rollers 49, 50, and 51 5 and the source of electric current supply. The reel comprises a stationary shaft 61 which passes through a bearing and has two spaced circular side plates 62 and 63 which form therebetween a circumferential groove. I mount a helical 10 spring 64 in the spaces intermediate the plates 62 and 63 and attach the inner end of the spring to the stationary shaft 61 and attach the outer end of the spring, by means of a pin 67, to one of the side plates whereby the reel 60 will be 15 uniformly impelled to one direction.

The flexible conductors 58 and 59 pass from the brushes 57 around the peripheral groove of the reel 60 and are firmly attached to the reel by means of a shoe 72 pressed into engagement 20 with the flexible conductors 58 and 59 by means of a screw 70 passing through an ear 71 on one of the plates of the reel, the spring 64 is arranged to exert a continuous pull upon that end of the flexible conductors which is attached to 25 the traveling distributing roller 51 so that when the rollers travel along their tracks to a position farther removed from their upper position the conductors 58 and 59 will be held taut though at the same time they will unwind from the reel 30 and when the traveling rollers are moved on their tracks closer to the reel the latter will wind the flexible conductors upon it thereby taking up any slack in said flexible conductors.

35 It will be apparent from an inspection of the drawings in connection with the foregoing description that in every instance I provide for contact of an electrically heated roller with an unheated one. In this way I am able to maintain all the rollers at the same temperature. 40 The temperature of the electrical elements are maintained by thermo couples in the manner more specifically described in my Patent No. 1,865,445. It is necessary to provide means for positively driving the ductor roller 21 at the 45 time of its contact both with the inking roller 3 and the cylinder inking roller 23. This can be done by means of gears which may be either toothed spur gears or grooved friction gears. My Reissue Patent No. 18,931 clearly describes means 50 for accomplishing this result.

Having described my invention what I regard as new and desire to secure by Letters Patent is:

1. In a platen press having a cylindrical inking roller, an ink fountain, a positively driven 55 ink fountain roller, a ductor roller, a traveling distributor roller, shafts for said rollers, supports for said shafts and a vertical type bed; an electrical heating element in the traveling distributor roller, flexible conductors to lead current to said element through its shaft, an electric heating element in the cylindrical inking roller, an electrical heating element in the ink fountain roller and a plurality of electrical heating elements in said type bed, said elements being connected to a source of electric current supply, means to control the temperature of said elements. 65

2. In a platen press having a cylindrical inking roller, an ink fountain, a positively driven 70 ink fountain roller, a ductor roller, a traveling distributor roller, shafts for said rollers, supports for said shafts and a vertical type bed; an electrical heating element in the traveling distributor roller, flexible conductors to lead cur- 75

- rent to said element, an electric heating element in the cylindrical inking roller, an electrical heating element in the ink fountain roller, and a plurality of electrical heating elements detachably mounted in said type bed, said elements being connected to a source of electric current supply, and means to control the temperature of said elements.
3. In a platen press having a cylindrical inking roller, an ink fountain, a positively driven ink fountain roller, a ductor roller, a traveling distributor roller, shafts for said rollers, supports for the shaft of said last named roller, and a vertical type bed; an electrical heating element in the traveling distributor roller, flexible conductors to lead current to said element, an electric heating element in the cylindrical inking roller, an electrical heating element in the ink fountain roller, and a plurality of electrical heating elements in said type bed, said elements being connected to a source of electric current supply, means to control the temperature of said elements, commutators on the shafts of the ink fountain roller and cylindrical inking roller connected to said elements, brushes which engage said commutators, electric conductors to convey current to said commutators.
4. In a platen press having a cylindrical inking roller, an ink fountain, a positively driven ink fountain roller, a ductor roller, a traveling distributor roller, shafts for said rollers, supports for the shaft of said last named roller, and a vertical type bed; an electrical heating element in the traveling distributor roller, flexible conduits to lead current to said element, an electric heating element in the cylindrical inking roller, an electrical heating element in the ink fountain roller and a plurality of electrical heating elements in said type bed, said elements being connected to a source of electric current supply, means to control the temperature of said elements, a commutator on the shaft of the traveling distributor roller, connected to said flexible conduits, brushes which engage said commutator, means carried by the shaft support to which said brushes are secured.
5. In a platen press having a cylindrical inking roller, an ink fountain, a positively driven ink fountain roller, a ductor roller, a traveling distributor roller, shafts for said rollers, supports for the shaft of said last named roller, and a vertical type bed, an electrical heating element in the traveling distributor roller, an electric heating element in the cylindrical inking roller, an electrical heating element in the ink fountain roller and a plurality of electrical heating elements in said type bed, said elements being connected to a source of electric current supply, means to control the temperature of said elements, means to control the temperature of said elements, means which permit said traveling distributor roller to move from a point adjacent said cylindrical inking roller to ink a plate on said type bed without disturbing the flow of current to said brushes.
6. In a platen press having a cylindrical inking roller, an ink fountain, a positively driven ink fountain roller, a ductor roller, a traveling distributor roller, shafts for said rollers, supports for the shaft of said last named roller, and a vertical type bed, an electrical heating element in the traveling distributor roller, an electric heating element in the cylindrical inking roller, an electrical heating element in the ink fountain roller and a plurality of electrical heating elements in said type bed, said elements being connected to a source of electric current supply, means to control the temperature of said elements, means which permit said traveling distributor roller to move from a point adjacent said cylindrical inking roller to ink a plate on said type bed without disturbing the flow of current to said brushes, commutators on the shaft of the traveling distributor roller, ink fountain and cylindrical inking rollers, brushes which contact said commutators, electrical conductors connected to said brushes.
7. In a platen press having a cylindrical inking roller, an ink fountain, a positively driven ink fountain roller, a ductor roller, a traveling distributor roller, shafts for said rollers, supports for said shafts and a vertical type bed; an electrical heating element in the traveling distributor roller, flexible conductors to lead current to said elements through its shaft, an electric heating element in the cylindrical inking roller, an electrical heating element in the ink fountain roller and a plurality of electrical heating elements in said type bed, said elements being connected to a source of electric current supply, means to control the temperature of said elements, and a take-up for said flexible conductors.

GEORGE A. RUTKOSKIE.
